SEALED CONTAINER WITH HINGED COVER

Marshall I. Williamson, New Haven, and Herman A. Carruth, Northford, Conn., assignors, by mesne assignments, to National Folding Box Company, Incorporated, a corporation of Connecticut

Application September 19, 1945, Serial No. 617,252

7 Claims. (Cl. 229—45)

1

This invention relates to sealed container with hinged cover and more particularly to a container comprising a box body having enclosing side walls and sealed top and bottom end walls and a hinged cover part attached to the box part and providing a convenient re-closure therefore when the adjacent sealed end of the box part has been opened.

In accordance with a preferred form of this invention, the box part of the container is formed and assembled from a paperboard blank presenting enclosing side wall panels, and top and bottom end sealing panels whereby a substantially sift-proof package is provided. The cover part which, preferably, is also formed and assembled from a paperboard blank, comprises a top wall panel adapted to cover the top sealed end of the box part, and enclosing flanges or side sections conforming to and adapted to telescope over the upper ends of corresponding side walls of the box part. The sealed top end of the box part is provided with a projecting flap or abutment element adapted to cooperate with an abutment flap or element associated with one of the enclosing flanges of the telescoping cover part in a manner to releasably resist hinging opening movement of the cover part and releasably retain the cover part in closed position.

When the hinged cover part has been raised from its releasably closed position, the sealed top end of the box part may be opened, for removal of contents in any of several ways, as by puncturing, cutting out a section or cutting off a corner. Preferably, however, the top end sealing panels of the box part are provided with a suitably cut and/or perforated lines defining a break-out area which may be removed to provide an opening through which the contents may be conveniently dispensed, as by pouring or with a spoon or other utensil.

After a desired amount of the contents has been removed from the box part, the hinged cover part may quickly and simply be returned to its original releasably secured closed position to cover the dispensing opening in the sealed top end of the box part and so provided continuing protection for the remainder of the contents against spilling and contamination.

Thus it will be appreciated that the hinged cover part provides a convenient and effective re-closure for the box part when the sealed top end of the box part has been opened for partial removal of its contents. Such a conveniently openable and re-closable container is particularly advantageous for the packaging of incrementally dispensable powdered or granular materials,

2

which are likely to spill from or become contaminated in a container which cannot be thus securely re-closed.

This improved container may be formed and assembled from substantially rectangular blanks of paperboard material, which blanks may be cut with a minimum of waste. The box part and the cover part are each so designed and constructed as to permit economical assembly thereof by the use of generally available box assembly machinery and without employing hand assembly methods or the use of specialized assembly equipment.

The container may be so designed and constructed as to permit partial assembly of the box blank as a collapsed shell by the carton manufacturer, which collapsed shells may be stacked together and shipped in a minimum of space along with the cover forming blanks. The flat body forming blanks or the collapsed body shells and the cover forming blanks may be conveniently assembled as needed by the merchandise manufacturer on automatic box assembly machines at a high speed of production and at relatively low cost.

An object of this invention is to provide a hinged cover container comprising a self contained box part with sealable end walls and a hinged cover part adapted to telescope over one end of the box part and enclose one of such sealable end walls therein, said cover part and the therein enclosed sealed box end wall having cooperating abutment elements adapted to releasably resist opening movement of the cover part.

Another object of this invention is to provide such a hinged cover container wherein the box part and the cover part are both formed from minimum waste blanks of paperboard material and designed to permit high speed and economical production on standard folding box manufacturing equipment.

A further object of this invention is to provide such hinged cover containers capable of high speed, economical, automatic assembly, filling and sealing on standard machines for so doing.

Other objects and advantages of this invention will become apparent as the disclosure proceeds.

In order that a more complete understanding of this invention and the advantages thereof may be made apparent, reference is made to the following description taken in connection with the accompanying drawings forming a part thereof, and, in which

Fig. 30 is a perspective view of the upper portion of the box part shown in Fig. 29 as the same appears before the final closing and sealing operation.

Fig. 31 is a perspective view of the upper portion of the box part formed from the blank shown in Fig. 25 showing the top end fully closed and sealed.

Fig. 32 is a perspective view of the partially assembled cover part assembled from the blank shown in Fig. 26, after application of adhesive.

Fig. 33 is a perspective view of the fully assembled cover part with adhesive applied to the hinge flap designed for attachment to the box part shown in Fig. 31.

Fig. 34 is a perspective view of the upper portion of the box part shown in Fig. 31 having the cover part shown in Fig. 33 applied and secured thereto, the cover part being shown in opened position.

Fig. 35 is a vertical cross sectional view of the upper portion of the fully assembled container shown in Fig. 34 as the same appears when the cover part is in closed position.

Fig. 36 is a vertical cross sectional view of the container shown in Fig. 34, this view illustrating the manner in which the abutment elements associated with the box part and cover part cooperate to releasably resist opening movement of the cover part.

Similar reference characters refer to similar parts throughout the several views of the drawings and specification.

Fig. 21 is a perspective view of the upper por-

trated in Figs. 1 to 13 inclusive, comprises a box part A assembled from the prepared blank shown in Fig. 1 and a cover part B assembled from the prepared blank shown in Fig. 2. The box forming blank shown in Fig. 1 comprises a plurality of enclosing panels which for simplicity in description may be referred to as a front wall panel 1, a rear wall panel 2, and side wall panels 3 and 4 hingedly connected in side by side relationship along parallel extending score lines 6. A securing flap 5 hinged to the side edge of the rear wall panel 2 along score line 7 is provided for securing to the free side edge of the side wall panel 4. A bottom forming tab 11 is hinged to the lower end of each of the side wall panels 3 and 4 along the score line 10. A bottom forming flap 8, hinged to the lower end of the rear wall panel 2 along the score line 10', is adapted to be folded over the inturned tabs 11 when the box part is assembled, and a bottom forming flap 9, hinged to the lower end of the front wall panel 1 along score line 10'', is foldable over the outside face of the bottom forming flap 8. The score lines 10' and 10'' are slightly out of alignment with each other and with the score lines 10 to permit folding assembly of the bottom forming tabs 11 and bottom forming flaps 8 and 9 to provide a firm and sturdy bottom for the box part.

A top wall forming tab 14 is hingedly connected to the upper end of each of the side wall panels 3 and 4 along the score line 13''. A top wall forming flap 12 is hingedly connected to the upper end of the rear wall panel 2 along the score line 13', and a top wall forming flap 15 is hinged to the upper end of the front wall panel 1 along the score line 13. The upper end of each of the top wall forming tabs 14 may be provided with a notch 19 to define an opening therebetween when the box part is assembled. A somewhat similar notch 20 may also be provided in the top wall forming flap 15, the notch 20 being shaped to match the opening formed by the notches 19 in the tabs 14 when the box part is assembled. And top wall forming flap 12 may have a punch-out area 18, defined by perforated lines 17 located to match with the notches formed in the tabs 14 and the flap 15, to provide a dispensing opening in the top wall of the box part when assembled. An abutment flap 16 hinged to the upper edge of the top wall flap 12 along the score line 21 provides means for releasably retaining the cover part in closed position as more particularly hereinafter described.

In assembling the prepared box forming blank shown in Fig. 1 into box form, adhesive is applied to the outside face of the securing flap 5. The enclosing panels 2 and 4 are folded toward each other about their corner defining score lines 6, and the securing flap 5 adhesively secured to the inside face of the side wall panel 4 along the free side edge thereof, thereby providing an expandable tubular construction as shown expanded in Fig. 3. In closing and sealing the bottom end of the box part, bottom forming tabs 11 are folded inwardly so as to extend substantially in alignment and adhesive is applied to their outer surfaces. Then bottom forming flap 8 is folded to overlie and adhere to the tabs 11, and adhesive is applied to its outside surface, whereupon bottom forming flap 9 is folded over and pressed into adhesive engagement with the outside face of flap 8, thereby completing assembly and sealing of the bottom end wall of the box part.

In forming and sealing the top wall of the box 75 their inner faces and also with the inner face

part, adhesive is applied to the outside face of the top wall forming flap 15 and this flap is then folded inwardly as shown in Fig. 4. The top wall forming flap 12 is folded downwardly and pressed into adhesive engagement with the flap 15 as shown in Fig. 5. Adhesive is also applied to the inside face of each of the top wall forming tabs 14 and these tabs are then folded inwardly and pressed into adhesive engagement with the outside face of flap 12, completing the assembly of the top wall of the box part as shown in Fig. 6.

It will be appreciated that the flaps and tabs constituting the bottom and top end walls of the box part may be folded and adhesively secured in closed position on carton end-sealing machines of standard design and that either the bottom end wall or the top end wall may be first closed and sealed and the box part filled with contents before the other end wall is closed and sealed. As shown in Fig. 6, the abutment flap or element 16 will overhang the upper end of the front wall panel 1 of the assembled box part, and it will be noted that the score line 21 for the abutment element 16 is preferably located slightly back from the front edge of the top wall when the box part is assembled so that a certain resistance to downward hinging movement of the abutment flap 16 is produced with a consequent tendency for the flap to spring or stand out from the front wall of the box part.

When the top wall forming tabs 14 and flaps 12 and 15 have been assembled to provide the top end wall of the box part as shown in Fig. 6, the punch-out portion 18 of the flap 12 will be in substantial alignment with the notch 20 in the flap 15 and the notches 19 in the tabs 14, so that access to the contents may be had by removing the punch-out portion 18. A box part for containing powdered or granular contents may thus be provided which is substantially leak-proof during shipment and storage, and yet which affords the user convenient access to the contents by merely removing the punch-out portion 18.

The cover part B as shown in Fig. 8 may be easily and quickly assembled from the blank shown in Fig. 2, the blank comprising a top wall panel 100 having side wall flanges 101 hinged thereto along score lines 102 and a front wall flange 104 hinged thereto along the score line 105. A corner forming tab 106 is hinged to one end of each of the side wall flanges 101 along the score line 107. A flange-reinforcing and corner-securing flap 108 is hinged to the front wall flange or panel 104 along score line 109. A further securing flap 103, for attaching the cover part to the box part, is hinged to the rear edge of the top wall panel 100 along the score line 104'.

In assembling the cover part from the blank shown in Fig. 2, the side wall flanges 101 are first raised to a position substantially at right angles to the top panel 100, and the corner tabs 106 folded inwardly so as to stand substantially in alignment along the crease line 105 as shown in Fig. 7. Adhesive is next applied to the inside face of the flange reinforcing and corner securing flap 108 and to a major portion of the front flange panel 104. The front flange panel 104 is then raised and pressed into adhesive engagement with the outer faces of the corner tabs 106 and the flange reinforcing and corner securing flap 108 is folded over the corner tabs 106 and pressed down into adhesive engagement with

of the front flange panel 104, thereby producing a fully assembled cover part as shown in Fig. 8.

It will be noted from Figs. 2, 7 and 8 that the front flange-reinforcing and corner-securing flap 108 of the cover part is of considerably less height or depth than the front flange panel 104 and that, with its longitudinal free cut edge 110, it thus forms a fixed abutment element upon the inside surface of the front flange panel of the cover part.

The cover part may be applied and secured to the box part by telescoping it over the sealed top end of the box part, thereby bending and forcing the abutment flap 16 down against the front wall panel 1 of the box part. While in this position, adhesive may be applied to the under side of the securing flap 103 of the cover part which flap may then be folded down and pressed into adhesive engagement with the back panel 2 of the box part as shown in Fig. 13.

When the cover part is thus secured in closed position, the longitudinal cut edge 110 of the cover abutment element 108 will directly underlie the abutment edge 22 of the box abutment element 16, thereby normally retaining the cover part in closed position. However, when lifting force is exerted on the front flange 104 of the cover part, compressive stress is exerted on the box abutment element 16 until the front flange 104 of the cover part has been lifted to a predetermined position at which the hinging abutment element 16 will release its grip on the cover abutment element 108 and subsequently permit the cover part to be freely swung into full open position. Thus the abutment elements 16 and 108 associated with the box part and cover part respectively cooperate to releasably retain the cover part in closed position and releasably resist opening movement of the cover part. The material from which the box part and/or cover part is formed is sufficiently flexible to permit this release resisting action of the two abutment elements.

It will be appreciated that the cover part B thus provides a convenient reclosable cover for the upper end of the box part when the break-out portion 18 of the top wall has been removed. Thus protection to the contents is provided at all times after the sealed top wall of the box part has been broken. The merchandise manufacturer is thus assured that his merchandise, when packaged in the container herein disclosed, is fully protected within the sealed box part, and the consumer is assured that after the top wall of the box part has been broken open to remove a portion of the contents, the remaining unused portion will continue to be protected by use of the conveniently reclosable hinged cover part.

The blank from which the box part is formed may be cut and scored by the carton manufacturer from large sheets or rolls of suitable paperboard material on an automatic cutting and scoring machine at a high production rate with a minimum of resultant paperboard waste. The sheets or rolls of paperboard material may be advantageously printed or lithographed before the cutting and scoring operation. Since only one face of the paperboard forms the outside face of the box part, the paperboard blanks or sheets need be finished and printed or lithographed on one side only. The carton manufacturer may assemble the box forming blanks into tubular form as shown in Fig. 3 and the partially assembled tubular box blanks shipped collapsed

in a minimum of space to the merchandise manufacturer. When the merchandise is packed therein the merchandise manufacturer, using a standard end sealing machine, may close and seal one end of the box part, fill the box part with contents, and then close and seal the other end.

The cover forming blank as shown in Fig. 2 may also be cut and scored by the carton manufacturer from large sheets or rolls of paperboard material which likewise need be finished and printed or lithographed on one side only, and the cover blanks may be shipped in a minimum of space to the merchandise manufacturer. The cover assembly operations as shown in Figs. 7 and 8 can be automatically performed on a standard box assembly machine, and at any time prior to shipment of the filled box part, the assembled cover part may be secured to the top end of the box part and swung into closed position. Substantial economies in manufacture, packaging and assembly results from the use of this improved hinged cover container, with the assurance that the merchandise within the container is fully protected during shipment, in storage and during the period the container is in use by the consumer.

There is shown in Fig. 14 to Fig. 24 inclusive, a hinged cover container of slightly modified construction, comprising a box part A' formed from the blank shown in Fig. 14 and a cover part B' formed from the paperboard blank shown in Fig. 15. The prepared paperboard blank shown in Fig. 14 is substantially similar to the blank shown in Fig. 1 except for certain details. As shown in Fig. 14, the top wall flap 12' hinged to the upper end of the rear wall panel 2 along score line 23'', carries an abutment flap 24 hinged to the front edge of the top wall flap 12' along score line 25. A top wall forming tab 14' is hinged to the upper end of each of the side wall panels 3 and 4 along a score line 23. A top wall forming flap 15' is hinged to the upper end of the front wall panel 1 along the score line 23'.

In assembling the box part A' from the blank shown in Fig. 14, the inclosing panels 1, 2, 3, and 4 are folded along the side edge defining score lines 6 to provide a tubular body, and the securing flap 5 is adhesively secured to the inside face of the adjacent free edge of the side wall panel 4.

The bottom end wall of the box part is assembled in a manner heretofore described by folding the bottom tabs 11 inwardly along the score lines 10, applying adhesive to the inside faces of bottom flaps 8 and 9 and folding flap 8 along the score line 10' so as to overlie and adhesively engage the tabs 11, then folding bottom flap 9 into firm adhesive engagement with the outside face of flap 8.

The top end wall of the box part A' is assembled by first folding in the tabs 14' and applying adhesive to the inside surfaces of flaps 15' and 12' including the associated abutment element 24 as shown in Fig. 17. Flap 15' is then folded inwardly and pressed into adhesive engagement with the inturned tabs 14' as shown in Fig. 18, and flap 12' is folded over and adhesively secured to flap 15'. Finally the abutment flap 24 is folded downwardly and pressed into adhesive engagement with the outside face of the front wall panel 1 as shown in Fig. 19.

A sealed box part is thus provided in which the contents are fully protected and which is substantially sift-proof in construction. The

merchandise contents may be inserted after either the bottom end or the top end of the box part is sealed, and after insertion of the contents, the remaining unclosed end closed and sealed. The box part forming blanks formed as shown in Fig. 14 are so designed that they need be finished and lithographed on one side only and may be cut and scored from large rolls or sheets of paperboard material at high production speeds and with a minimum of waste. Blanks may be assembled in tubular form by the carton manufacturer and shipped to the merchandise manufacturer in collapsed form so as to occupy a minimum of space. The merchandise manufacturer may complete the assembly of the box part by the use of standard machines, usually proceeding by sealing one end of the partially assembled box part, inserting the contents, and then sealing and closing the other end.

There is illustrated in Fig. 20 a cover part B' of somewhat modified form which may be assembled from the prepared paperboard blank shown in Fig. 15. The blank shown in Fig. 15 comprises a top wall panel 100 having a front flange section 104 hinged to the front edge thereof along a score line 105, and a securing flap 103 hinged to the rear edge thereof along the score line 104'. A side wall forming flange 101 is hinged to each end of the front flange 104 along the score line 113. A securing tab 111 is hinged to an edge of each side flange 101 along a score line 112. An abutment flap 108' is hinged to an edge of the front flange 104 along the score line 109, which score line forms the lower edge of the front flange when the cover part is fully assembled. The cover forming blank shown in Fig. 15 may be cut and scored from large sheets of paperboard material and need be finished and lithographed or printed on one side thereof only. The prepared cover forming blanks may be shipped flat to the merchandise manufacturer for assembly as needed.

In assembling the blank shown in Fig. 15 to provide a cover part as shown in Fig. 20, the front flange 104 is erected to extend substantially at right angles to the top wall panel 100, side flanges 101 are folded to extend at right angles to the front flange 104, with the securing tabs 111 positioned to overlie either the inside face or the outside face of the top wall panel 100. The tabs 111 are secured to the top wall panel 100 by suitable adhesive. It will be noted that the securing tabs 111 serve to reinforce and strengthen the top wall panel 100 and when secured thereto retain the front flange 104 and the side flanges 101 in rigid right angular relationship to the top wall panel 110. It will be further noted that the abutment flap 108' is free to hinge about the score line 109 and is not adhesively secured to the inside face of the front flange 104.

The cover part is secured to the box part by applying adhesive *g* to the inside face of the securing flap 103, which is then pressed into adhesive contact with the outside face of the rear wall panel 2 of the box part in a manner so that score line 104' provides a hinge for the cover part directly adjacent to the score line 23'' which defines the upper edge of the rear wall panel 2 of the box part. The cover part is so formed that the side flanges 101 thereof will snugly telescope over the adjacent side wall panels 3 and 4 of the box part and the front flange 104 will snugly telescope over the front wall panel 1 of the box part.

When the cover part is in closed position as shown in Figs. 22 and 23, the upturned abutment

edge 110' of the hinged abutment flap 108' of the cover part will extend under and substantially abut the abutment edge 22' of the fixed abutment element 24 of the box part. When lifting force is exerted upon the front flange 104 of the cover part, the abutment flap 108' will execute a hinging movement as shown in Fig. 24, and during this initial opening movement compressive stress will be exerted upon the hinged abutment flap 108' and continued until enough lifting force has been applied to the cover part to cause sufficient flexure of the front flange 104 or other parts of the container to permit complete opening movement of the cover part.

To obtain access to the contents of the container after the cover part has been swung to open position, the top end wall of the box part may be opened in any of several ways, as by puncturing, cutting out a section, or cutting off a corner as indicated at *x* in Fig. 21. Thus it will be appreciated that the hinged cover part serves an important purpose in providing a protective closure for the upper end of the box part when punctured, cut or broken out at any area covered by the re-closable cover part.

There is shown in Figs. 25 to 36 inclusive a hinged cover container of further modified construction, comprising a box part A' formed from the blank shown in Fig. 25 and an attached cover part B'' formed from the blank shown in Fig. 26. The box forming blank A' may be cut and prepared from paperboard material finished or lithographed on one side thereof only. The blank comprises a front wall panel 31 and a rear wall panel 32 hingedly connected along the parallel extending score lines 34 and 35 to a bottom wall panel 33. Side wall forming panels 40 are hingedly connected by the parallel extending score lines 37 to the opposite side edges of the front wall panel 31. Securing flaps 36 and hingedly connected to the opposite side edges of the rear wall panel 32 along the parallel extending score line 37'. Bottom tabs 38 are also hingedly connected along parallel extending score lines 37' to the opposite side edges of the bottom panel 33. The paired score lines 37 are slightly out of alignment with the paired score lines 37' to facilitate assembly of the blank into box part form.

The top end of the box part is formed by the paired top wall forming tabs 42 hinged to the upper end of the paired side wall panels 40 along the respective score lines 43. A top wall flap 41 is hinged to the upper end of the front wall panel 31 along a score line 43', the score line 43' being slightly out of alignment with the score lines 43. A second top wall flap 44 is hinged to the upper end of the rear wall panel 32 along the score line 45. The tabs 42 are each provided with a wing extension 46 hinged to the inner side edges of each tab which serve to provide abutment elements to releasably retain the hinged cover part in closed position. The tabs 42 may each be provided with a notch cut-out 49 to provide an aperture therebetween when the top end of the box part is assembled. A cut-out 48 formed in the top wall flap 41 and a tear-out section 51 defined by the perforated line 50 in the top wall flap 44, provide means for forming a dispensing opening in the top wall of the container.

The box forming blanks A' may be stacked together in flat condition and shipped to the merchandise manufacturer for assembly as needed.

The blanks are adapted to be assembled on a standard box assembling machine which operates, first, to apply adhesive to the inside faces of the

11

side wall forming panels 40 and then, by means of a plunger, to drive the bottom wall panel 33 into a pocket provided, at its mouth, with guides which, in proper sequence, raise the back and front wall panels 31 and 32 and turn in the bottom tabs 38, the securing flaps 36 and the side wall forming panels 40 to a position substantially at a right angle respectively to the bottom wall panel 33, the back wall panel 32 and the front wall panel 31, the sequence being such that the adhesive bearing side wall forming panels 40 are turned in last to overlie and be pressed into adhesive engagement with both the bottom tabs 38 and the securing flaps 36, thus providing an assembled box part with open top end as shown in Fig. 28.

It will be noted that the lower ends of the securing flaps 36 are provided with a mitered edge 39 which is designed to substantially abut the adjacent mitered edge 39' of the adjacent bottom tabs 38, as shown in Fig. 27.

The box part may then be filled with merchandise through the opened upper end thereof whereafter the top end sealing operation may be performed. In sealing the top end wall, adhesive is applied to the outside face of the top wall flap 41 and to the inside face of the top wall flap 44. Flap 41 is then turned in, as shown in Fig. 29, followed by the tabs 42, which are pressed into adhesive engagement with the outer face of flap 41, as in Fig. 30, and then flap 44 is pressed into adhesive engagement with the outer faces of the tabs 42. This completes the sealing of the top end wall of the box part, the thus sealed box appearing as shown in Fig. 31. When the top wall has been thus assembled, the abutment flaps or elements 46 hinged to the tabs 42 will overhang the front wall panel 31 as shown in Figs. 31 and 32.

The cover part B'' to be attached to the assembled box part A'' comprises a top wall panel 100 having side wall flanges 101 hinged to the opposite side edges thereof along score lines 102, a securing flap 103 hinged to the rear edge of the top wall panel along score line 104', a front wall flange 104 hinged to the front edge of the top wall panel 100 along score line 105, and a corner forming securing tab 106 hinged to each of the side flanges 101 along score line 107. The securing tabs 106 have end extensions 106' of reduced width so that each tab presents an abutment edge 108'. The cover forming blanks B'' may be stacked together in flat condition and shipped to the merchandise manufacturer for assembly as needed. These blanks may be assembled on a standard box assembling machine which operates, first, to apply adhesive to the inside face of the front wall flange 104 at opposite ends thereof in a pattern substantially the size and shape of the corner-forming securing tabs 106; then, by means of a plunger, to drive the top wall panel 100 into a pocket equipped with guides which, in proper sequence, raise the side wall flanges 101 to a position at right angles to the top wall panel, turn the corner forming tabs 106 in at right angles to the side wall flanges, and raise the front flange 104 also at right angle to the top wall panel and into adhesive engagement with the corner tabs 106.

To attach the cover part B'' to the box part A'', adhesive is applied to the inside face of the securing flap 103 of the cover part and the cover part then pressed into adhesive engagement with the outside face of the rear wall panel 32 of the

12

box part in a manner so that the hinging score line 104' of the cover part is positioned closely adjacent to the score line 45 which defines the upper end of the rear wall panel 32 of the box part. The cover part is proportioned and designed so that the top wall panel 100 thereof will cover the upper end of the box part with the side flanges 101 and front flange of the cover part snugly telescoping over the upper ends of the side wall panels 40 and front wall panel 31 of the box part. When the cover part is in closed position the abutment edge 108' of the corner tab extension 106' of the cover part will substantially abut the abutment edges 46' of the downturned hinged abutment flaps 46 associated with the box part.

The cover part B'' may be opened by applying an upward lifting force to the front flange 104, thereby imposing compressive stress on the hinged abutment flaps 46 as shown in Fig. 36. It will be appreciated that the abutment flaps or elements 46 and 106' associated with the box part and cover part respectively, cooperate to resist opening movement of the cover part, so that only after the cover part has been forcibly lifted to a predetermined position may the cover part be swung freely into full open position as shown in Fig. 34. Access to the contents P in the box part may be had by severing and removing the tear-out section 51, thereby providing a dispensing opening. Thereafter the hinged cover part serves as a closure for the box part and prevents spilling or the entry of foreign matter into the box part through the pouring opening.

From the illustrated embodiments above described it will be observed that hinged cover containers may be provided which can be simply and economically formed and assembled from two separate and substantially rectangular blanks of paperboard material, one blank designed to form the box part and the other blank designed to form the cover part. The cover part is provided with a securing flap or other means for hingedly securing the cover part to the rear wall of the box part. An important feature of this invention is the provision of a box part comprising top wall forming flaps and tabs which may be assembled to provide a sealed top end wall for the box part so that the box part provides a substantially sift-proof package in which the contents are adequately protected. The top wall of the box part may however be provided with break-out portions or sections to provide a dispensing opening through which the contents may be removed, the cover part then serving as a closure for the opened top wall of the box part, thereby protecting the contents from contamination and loss through spillage when the sealed top wall of the box part is broken. It will be particularly observed that the abutment flaps or elements associated with the box part are formed as a part of one of the top wall forming flaps or tabs and are so arranged and located that the abutment element or flap so formed may be folded to overlie the outside face of the front wall panel of the box part to cooperate with a companion abutment element associated with the cover part to releasably retain the cover part in closed position and releasably resist opening movement thereof.

It will be noted that the hinging abutment flap may be associated with either the box part or the cover part, and alternatively the complementary fixed abutment flap or element may be associated with either the box part or the cover part, it being

preferable to provide for hinging movement of one of the abutment flaps while the other abutment flap is secured in fixed position. It will also be appreciated that the top wall forming tabs and the two top wall forming flaps forming a characteristic part of the top wall of each of the box parts illustrated, may be folded and secured together in various sequences to provide a substantially three-ply top wall for the box part. In other words, the top wall forming tabs may be first folded in position with the top wall forming flaps folded consecutively thereover as illustrated for example in Fig. 17, or one of the top wall forming flaps may be first infolded and the top wall forming tabs next infolded to provide the intermediate layer of the three-ply top wall Fig. 30 or both of the top wall flaps may be first infolded and the top wall tabs folded thereover to provide the outer layer or ply of the top wall in the manner shown in Fig. 6. Thus the various elements which form the box part and the cover part in the various illustrated embodiments may be arranged various ways to achieve the novel and advantageous characteristics of this invention.

It will be therefore appreciated that various omissions, substitutions and re-arrangements may be made by those skilled in the art without departure from the novel concept and spirit of this invention as defined by the annexed claims.

What is claimed is:

1. An improved hinge cover container comprising, a box part having a plurality of enclosing side panels forming a tubular body, a bottom wall panel closing the bottom end thereof, a plurality of inturned flaps respectively hinged to the upper ends of certain of said inclosing side panels of the box part providing a plural-ply top wall panel for the box part, a hinged cover part having an end wall panel adapted to cover the top wall panel of the box part, means for hingedly connecting said end wall panel to one of the enclosing side panels of the box part, cover flange panels joined to said cover end panel adapted to telescope over corresponding enclosing side panels of the box part, cooperating abutment elements associated with one of the cover flange panels and a free edge of one of the top wall flaps of the box part, said abutment elements being operative to releasably retain the cover part in closed position and releasably resist opening movement thereof, said top wall panel of the box part having means to provide a contents removing therein, said cover part when in closed position being designed to provide a closure for such opening.

2. An improved hinge cover container comprising, a box part having a plurality of enclosing side panels forming a tubular body, a bottom wall panel closing the bottom end thereof, a plurality of inturned flaps respectively hinged to the upper ends of certain of said inclosing side panels of the box part providing a plural-ply top wall panel for the box part, a hinged cover part having an end wall panel adapted to cover the top wall panel of the box part, a securing flap hingedly connecting said end wall panel to one of the enclosing side panels of the box part, cover flange panels joined to said cover end panel adapted to telescope over corresponding enclosing side panels of the box part, and cooperating abutment elements operative to releasably retain the cover part in closed position and releasably resist opening movement thereof, one of said abutment elements comprising an abutment flap hinged to a

free edge of one of the top wall forming flaps of the box part and normally overhanging one of the inclosing side panels thereof, said other abutment element being fixed to the inside face of the corresponding flange panel of the cover part.

3. An improved hinge cover container comprising, a box part having a plurality of enclosing side panels forming a tubular body, a bottom wall panel closing the bottom end thereof, a plurality of inturned flaps respectively hinged to the upper ends of certain of said inclosing side panels of the box part providing a plural-ply top wall panel for the box part, a hinged cover part having an end wall panel adapted to cover the top wall panel of the box part, a securing flap for hingedly connecting said end wall panel of the cover part to one of the enclosing side panels of the box part, cover flange panels joined to said cover end panel of the cover part adapted to telescope over corresponding enclosing side panels of the box part, and cooperating abutment elements operative to releasably retain the cover part in closed position and releasably resist opening movement thereof, one of said abutment elements comprising an abutment flap extending from a free edge of one of the top wall forming flaps of the box part and overhanging the outside face of the adjacent enclosing side panel thereof, said other abutment element comprising an abutment flap associated with one of the corresponding flange panels of the cover part and normally overlying the inside face thereof.
4. An improved hinge cover container comprising, a box part formed from a single blank of paperboard material presenting enclosing front, rear and side wall panels providing a tubular body, a bottom wall panel enclosing the bottom end thereof, inturned top wall forming tabs hinged to the upper ends of said side wall panels, a top wall forming flap hinged to the upper end of said rear wall panel, and a top wall forming flap hinged to the upper end of said front wall panel, said tabs and flaps providing a plural-ply top wall panel for the box part, a cover part having an end wall panel adapted to cover the top wall panel of the box part, means for hingedly connecting said end wall panel of the cover part to the upper end of the rear wall panel of the box part, cover flange panels joined to said cover end panel adapted to telescope over the corresponding side panels and front panel of the box part, cooperating abutment elements operative to releasably retain the cover part in closed position and releasably resist opening movement thereof, one of said abutment elements being connected to the inside face of the front flange of said cover part and said other abutment element being integral with and extending from the front free edge of said first named top wall forming flap of the box part and adapted to overhang the outside face of the front wall panel thereof, one of said abutment elements comprising a hinging flap.
5. An improved hinge cover container comprising, a box part formed from a single blank of paperboard material presenting enclosing front, rear and side wall panels providing a tubular body, a bottom wall panel enclosing the bottom end thereof, inturned top wall forming tabs hinged to the upper ends of said side wall panels, a top wall forming flap hinged to the upper end of said rear wall panel, and a top wall forming flap hinged to the upper end of said front wall panel, said tabs and flaps providing a plural-ply

top wall panel for the box part, a cover part having an end wall panel adapted to cover the top wall panel of the box part, means for hingedly connecting said end wall panel of the cover part to the upper end of the rear wall panel of the box part, cover flange panels joined to said cover end panel adapted to telescope over the corresponding side panels and front panel of the box part, cooperating abutment elements operative to releasably retain the cover part in closed position and releasably resist opening movement thereof, one of said abutment elements being connected to the inside face of the front flange of said cover part and said other abutment element being integral with the free front edge of one of said top wall forming tabs of the box part and adapted to overhang the outside face of the front wall panel thereof, one of said abutment elements comprising a hinging flap.

6. An improved hinge cover container comprising, a box part formed from a single blank of paperboard material presenting enclosing front, rear and side wall panels providing a tubular body, inturned top wall forming tabs hinged to the upper ends of said side wall panels, a top wall forming flap hinged to the upper end of said rear wall panel, and a top wall forming flap hinged to the upper end of said front wall panel, said tabs and flaps providing a plural-ply top wall panel for the box part, a cover part having an end wall panel adapted to cover the top wall panel of the box part, means for hingedly connecting said cover end wall panel to the upper end of the rear wall panel of the box part, cover flange panels joined to said cover end panel adapted to telescope over the corresponding side panels and front panel of the box part, a pair of cooperating abutment flaps operative to releasably retain the cover part in closed position and releasably resist opening movement thereof, one of said abutment flaps being fixed to the inside face of the front flange panel of said cover part and said other abutment flap being hinged to the free front edge of one of said top wall forming tabs of the box part and adapted to overhang

45

the outside face of the front wall panel thereof.

7. An improved hinge cover container comprising, a box part having a plurality of enclosing side panels forming a tubular body, a bottom wall panel closing the bottom end thereof, a plurality of inturned flaps respectively hinged to the upper ends of certain of said enclosing side panels of the box part providing a plural-ply top wall panel for the box part, a hinged cover part having an end wall panel adapted to cover the top wall panel of the box part, means for hingedly connecting said end wall panel to one of the enclosing side panels of the box part, cover flange panels joined to said cover end panel adapted to telescope over corresponding enclosing side panels of the box part, cooperating abutment elements associated with one of the cover flange panels and a free edge of one of the top wall flaps of the box part, said abutment elements being operative to releasably retain the cover part in closed position and releasably resist opening movement thereof, said cover part when in closed position providing a secondary closure for the plural-ply top wall panel of the box part.
